DESIGN FOR AN APPARATUS FOR THREADING SEWING NEEDLES

David Robert Ligh, Staten Island, N. Y.

Application May 25, 1940, Serial No. 92,583

Term of patent 7 years

To whom it may concern:

Be it known that I, David Robert Ligh, a citizen of the United States of America, residing at Staten Island, in the county of Richmond, State of New York, have invented a new, original, and ornamental Design for Apparatus for Threading Sewing Needles, of which the following is a specification, reference being had to the accompanying drawing, forming a part thereof.

Fig. 1 of the drawing is a perspective view of my new design for an apparatus for threading sewing needles;

Fig. 2 is a plan view of my design; and

Fig. 3 is a front view of my design.

I claim:

The ornamental design for an apparatus for threading sewing needles, as shown.

DAVID ROBERT LIGH.
